CLAIM

The ornamental design for a stacking kit for washing machine and dryer, as shown and described.

DESCRIPTION

FIG. 1 is a first perspective view of a stacking kit for washing machine and dryer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is another perspective view of the stacking kit for washing machine and dryer without the cornered panels; and,

FIG. 10 is an enlarged view of the selected portion 10 in FIG. 1.

The broken lines shown in the drawings depict portions of the stacking kit for washing machine and dryer that form no part of the claimed design. The dot-dashed broken line indicates cutoff boundaries for the enlarged detailed portion views and forms no part of the claimed design.
